UNITED STATES PATENT OFFICE

ALFRED ERNEST HUDD, OF LIVERPOOL, ENGLAND, ASSIGNOR, BY MESNE ASSIGNMENTS,
TO AUTOMATIC ELECTRIC INC., OF CHICAGO, ILLINOIS, A CORPORATION OF DELA-
WARE

TRAIN-CONTROL SYSTEM

Application filed January 8, 1926, Serial No. 79,932, and in Great Britain December 9, 1925.

The present invention concerns improvements in or relating to train control systems and has for its object the reduction of the size of ramps employed to only a few feet 5 in length, avoidance of electrical energy on the locomotive for brake controlling purposes, and the positive opening of the air pipe every time the train passes a controlling ramp, irrespective of whether the ramp is connected to 10 a source of electrical energy or not, a fresh operation being required to close the air pipe.

One of the features of the present invention concerns the employment of electrolytic cells on the train which act in the same manner as large capacity condensers provided the voltage to which they are subjected is not too high. Large capacity condensers if sufficiently cheap as regards cost could be employed in 15 the place of the electrolytic cells without departing from the spirit of the invention. The object of a large capacity condenser is that it can receive a much larger quantity of electricity from a momentary contact with a source of direct current electrical energy than 20 can be obtained from connecting an inductance such as an ordinary electromagnet. Consequently it is possible by shunting an electromagnet with a large capacity to receive enough energy from a ramp connected to a source of 25 potential if the ramp is small and the speed of the train is high to enable the electromagnet to be energized although the electromagnet could not be energized if the condenser were missing. Incidentally, as the condenser 30 receives the charge, the electromagnet may be ultimately energized by the discharge of the condenser after the shoe has left the ramp; this naturally leads to the second feature of 35 the invention which is a marked advance over prior systems.

This feature consists of means whereby a valve is always positively opened whenever a train passes over a ramp, but if the ramp is connected to a suitable source of potential 45 the effect of the opening of the valve to bring about the application of the brakes is prevented. This distinguishes from prior arrangements in which a valve is permitted to open and is therefore dependent on the removal of holding means whereas by the pres-

ent invention a definite operation has to take place to prevent the opening of the valve becoming effective, such as the closing of another valve, or possibly the same valve, if the duration of contact of the shoe with the 55 ramp is sufficiently short.

A further feature of the invention is the provision of a time element device carried on the locomotive and contactors or ramps of short length on the side of the track thus providing a selective speed control which is infinitely adjustable to the track conditions in territories having different signalling conditions and regulations.

One arrangement for carrying out the invention will be described by way of example only with reference to the accompanying drawings, in which Fig. 1 shows the brake controlling arrangements. Fig. 2 shows the arrangement of contactor shoes, and a contactor at the side of the track, Fig. 3 illustrates diagrammatically an application of the system to three position automatic signalling, while Fig. 4 shows, in operated position, a portion of the mechanism shown at 75 normal in Fig. 1.

A contactor 1 consists of a bar or plate shaped as shown, of a length which need not be longer than a few feet. This is really a very small ramp, when compared with those usually used which are from 100 to 150 feet in length. The shoes consist of two fixed brushes 5 and 6, and a movable brush 3. The fixed brushes serve for cleaning the contactor so as to ensure a good electrical connection, while the movable brush 3 is connected to a slidable carrier 4 running in vertical ball races 40^a, 41. The carrier 4 is provided with a tapered portion so that it is narrower at its upper end than at its lower 90 end. This tapering is so arranged that on the upward movement of the carrier, a roller 41^a carried on the end of a shaft 42 terminating in a piston 8^a moves to the right with the shaft and piston. The shaft in turn acts on 95 a ball 43 to force the ball upwards and thereby the valve stem 7 of a valve 44. The valve 44 is thereby opened and is mechanically held open until a force of compressed air on the piston 8^a causes the piston and its 100

associated parts to move to the left which of course can only take place when the brush 3 has come off the contactor 1.

The brush 3 has connected to it a conductor 40, which has a branch lead extending direct to the upper terminal of winding 36 and ground, and a second branch extending through the contacts 37 and resistance 38 in multiple, to the ungrounded terminals of the group of electrolytic cells 17 and polarized electromagnet 18 in multiple, respectively to ground. In view of the foregoing it will be appreciated that the three elements 17, 18, and 36 are in a multiple bridge across one or the other of the batteries 16' or 21 when an energized contactor is engaged by the brush 3.

The electromagnet 36 is of high resistance, is therefore very sluggish to operate, and is never operated unless the vehicle is stopped with brush 3 in engagement with a contactor having current connected thereto, so that current can be supplied to it for an appreciable time.

It will first be assumed that positive current is connected to the first encountered contactor, that is to say, the positive of the battery 16', the negative of which is connected to the rails. This is the condition which exists when the signal associated with the contactor is at "clear" as will presently appear. When positive current is picked up by the brush 3 the cells 17 become charged and upon discharging, supply current direct from the ungrounded terminal of these cells to the electromagnet 18, i. e., from the ungrounded terminal of these cells to the upper terminal of 18, in the proper direction to cause it to rotate its armature 19 in an anti-clockwise direction. A small portion of the current discharged from the cells 17 also flows from their grounded terminal to the lower terminal of solenoid 36 and from their ungrounded terminal through the contacts 37 and resistance 38 in multiple to the upper terminal of the solenoid 36. The solenoid 36 is however not operated because the current flow from cells 17 is of too short a duration.

We will now again direct attention to the polarized relay 18. The armature 19, it will be noted, is pivoted at 46 and is engaged by a sliding member 47 running in guides 48 and 49 in such a manner that the sliding member must be forced to the right if the armature moves in either a clockwise or an anti-clockwise direction from the position shown. The sliding member engages a rod of the valve 20 which allows air to escape from the pipe 10 to atmosphere. Consequently when the electromagnet 18 is energized with the positive current valve 20 becomes closed. Therefore the net result of the shoe passing over contactor 1 is to first open valve 44 mechanically and secondly to close valve 20 by electromagnetic means. The result is that compressed air from the chamber

8, which is normally maintained full by air admitted from the main air-pipe 50 through a restricted orifice 35, is first admitted through the valve 51, to pipe 9, and thence through the valve 44 to pipe 10, but its escape to atmosphere is prevented owing to valve 20 being closed. It serves, however, to admit compressed air to the righthand side of piston 8^a, so that when the shoe 3 falls after passing the contactor 1, the piston 8^a is immediately moved back to the left and the valve 44 automatically closes. An instant later armature 19 is restored to its neutral position, again opening valve 20. Consequently it will be appreciated that the net result of passing over a positively charged contactor is nil as regards producing any braking effect, so that when a signal is at clear the train passes freely. If desired the armature 19 of the electromagnet 18 could be provided with a pointer or any other suitable indication could be given to notify the engineer when a contactor was passed and to assure him that it was in proper working order.

Assume however that instead of passing over a positively charged contactor the shoe passed over a negatively charged contactor, that is, a contactor connected for instance to the negative pole of battery 21. In this case the mechanical opening of the valve 44 will be the same as hitherto. However, the electromagnet 18 will be energized by current flowing in the opposite direction so that the armature 19 will move in a clockwise direction. This will have the same effect as regards the closing of the valve 20, but armature 19 is provided with an abutting projection 52 which normally engages a pivoted catch 26', which in turn engages a roller on the end of a rod 53 secured to a diaphragm 26. The catch 26' normally serves to hold up the pivoted member 25, by which the valve rod 22 of a valve 54 is held closed. Accordingly when the armature 19 moves in a clockwise direction, the catch 26' is moved to the right, thereby permitting the pivoted member 25 to fall until it encounters the top end of armature 19. This permits the valve 22 to open. When the catch 26' is moved to the right the sector 24, which is connected by bracket 57 to catch 26', is moved clear of the roller 27 and accordingly rotates slightly over one-fourth revolution into the position in which it is shown in Fig. 4. An instant later the armature 19 is restored to its neutral position and the pivoted member 25 then falls onto the abutment 52 on the armature 19, thereby locking the armature 19 against clockwise movement until a predetermined time has elapsed, at the end of which, member 25 is restored to the initial position in which it is shown in Fig. 1 as will later appear.

These operations are brought about as a result of the opening of valve 54. When this

valve is opened air is admitted to a jet 19', to a whistle 23, and also is applied against diaphragm 26. The air pressure against diaphragm 26 is effective to bring and maintain sector 24 into engagement with the roller 27. The whistle gives an audible signal while the air passing through the jet 19' impinges against the vanes of a small turbine 20. This turbine supplies the driving power for the timing device, which is controlled by a standard type of anchor pallet spring balance wheel escapement 18^a, so that its movement is always at a fixed speed; in other words the turbine simply replaces the driving spring in a clockwork movement. The turbine therefore turns round and by means of a suitable gearing drives the roller 27 at a predetermined speed, while the roller in turn rotates the sector 24 in a clockwise direction, until the sector 24 can no longer prevent lever 57 and catch 26' from moving to the left. At this time the pressure on diaphragm 26 becomes effective to restore catch 26' and the pivoted member 25 to their initial position shown in Fig. 1. It will be understood that the speed of the roller 27 may be varied as desired by adjusting the balance wheel or by altering the length of the contact face of sector 24 or the diameter of roller 27. If the driver of the train observes the warning given by the whistle, he will reduce the speed of his train so that, before the next contactor is reached, the roller 27 will have caused the sector 24 to rise sufficiently to permit air pressing on diaphragm 26, due to valve 54 being open, to force the catch 26' to the position shown in Fig. 1, to again permit clockwise movement of armature 19. If, however, before the timing mechanism has completed its cycle negative current is again received, due to the shoe 3 passing over another contactor 1, the armature 19 being locked will be unable to move in a clockwise direction and consequently the valve 20 cannot be closed. The valve 44 will therefore continue to be held open by the shaft 42 as the pipe 10 is open to atmosphere. Therefore no pressure is built up for actuating piston 8^a to restore the shaft 42 to the left. The escape of air from chamber 8 to atmosphere, via pipe 9, valve 44, pipe 10 and valve 20 will therefore permit the diaphragm 12 to collapse. This results in the opening of the valve 13, which permits air to flow from the main air pipe 50, through the pipe 60 and to the piston 15. The piston 15 thereupon moves to the left in the cylinder 14 and, acting on the roller 61 connected to a special handle pivoted as shown, will cause this handle to rotate and move to the position corresponding to a service application of the brakes.

It will be noted that the brake lever is made in the form of a Y or three branch lever, one branch being free and serving as a handle for manual operation; the second branch ex-

tends into the associated cylinder 14 into engagement with the piston 15 so that the piston can operate it about its pivot, which is located at the end of the third branch of the Y. The pivoted branch is located just outside the cylinder and is so proportioned with respect to the branch within the cylinder that the latter branch is free to move linearly within the cylinder for a distance sufficient to rotate the lever through substantially one-fourth the arc of a circle.

It should be understood that this special handle can be used for applying the brakes in the ordinary way, its motion being as will be seen, independent of the piston 15 when it is employed for applying the brakes. A small pin hole 63 is provided in the cylinder 14 to enable the handle to be returned to the releasing position when the pressure on 15 is released.

The third case which might arise is that the contactor 1 is de-energized, that is to say, it is connected to neither positive nor negative current. In such a case the shoe 3 will be raised and the valve 44 opened. Valve 20 will also remain open so that air in the chamber 8 can at once escape to atmosphere. Consequently diaphragm 12 collapses and the service application of the brakes follows as previously described.

It may occasionally happen that a train, in pulling into a station, or because of some trouble, such as a hot box, will find it necessary to stop and in the ordinary stopping, happen to bring the shoe on top of a contactor.

In order to avoid any danger of excessive current drain due to a train's coming to rest with the shoe 3 on the top of a contactor 1, an electromagnet 36 is provided. This electromagnet, as previously explained, is of high resistance and is of the solenoid type, so that it will not become energized under ordinary circumstances due to its sluggishness, but in the case under consideration where current will be received for a longer time than usual the electromagnet 36 will become energized. In doing so it closes the valve 51 thereby permitting the chamber 8 to become filled through the aperture 35 and opens the contact 37, thereby inserting the resistance 38 in series with the branch circuits extending to ground via the electromagnet 18 and cells 17, respectively, so as to avoid excessive battery drain.

Arrangements can conveniently be provided for reverse running so that the train control would be operative in whichever direction the engine were running. For this purpose a locomotive would conveniently be provided with a plunger and fixed brush assembly on each side similar to the plunger 4 and the fixed brushes 5 and 6. Pipes 9 and 10 however would be taken through two-way cocks, while a connected wire 40 would be

70

130

taken through a two-way switch, so that when the engine were running in one direction one set of shoe brushes with their associated mechanism would be operative, while when the train were running in the reverse direction the other set of brush and shoe mechanism would be operative. The two-way cocks and the two-way switch would be attached to the reverse lever of a locomotive, so that either set could be brought into action according to the direction of travel. In single line operation the ramps would be provided on the other side of the track and brought into use according to the direction of traffic as is common in most train control systems.

In Fig. 3 an arrangement is shown of the application of the invention to a railway in which three position automatic signalling is employed, and in which each signal controls the connection of battery potential to a plurality of ramps. The first signal, A, which is shown in the "all clear" position controls the first two contactors C¹, C². Under clear track condition positive current is connected to both these contactors. Consequently a train passing from right to left would pass these contactors as described above without having any automatic application of the brakes. Contactors C³, C⁴ and C⁵ are controlled by signal B, which is shown in the cautionary position, which means that the next signal, signal C, is at danger. The cautionary signal controls the contactors C³, C⁴ and C⁵. C³ and C⁴ have positive potential connected thereto, while C⁵ has negative potential connected thereto. Consequently C³ and C⁴ are passed similarly to C¹ and C², but when C⁵ is reached, there is negative current on the contactor, and consequently the whistle blows giving a warning to the driver to slow up, and future operation depends upon whether he does so or not. The signal C is at danger and controls the contactors C⁶, C⁷, and C⁸, all of which are connected to negative potential.

Now if the driver of an oncoming train after receiving negative current from the contactor C⁵ neglects to reduce his speed sufficiently, the contactor C⁶ will be reached and the brakes will be automatically applied as described. If, however, he has reduced his speed sufficiently so that he does not reach the contactor until the time fixed by the time element device has elapsed, then he simply receives a further warning signal. Of course it may be that in the meanwhile the contactor C⁶ has been connected to positive battery owing to the signal C having been raised either to the mid position or to the "all clear" position in which case the whistle would not be sounded when passing C⁶ and even in a fog the driver may be advised by observation of the movement of armature 19 of electromagnet 18 that all is clear, and that he

can speed up again. Normally, however, it can be assumed that he receives the negative signal and therefore he knows that he must keep down his speed. Therefore, he will still keep running at the reduced speed until he reaches contactor C⁷. Here again he receives a warning signal, but by this time his speed must have been reduced very considerably, say for instance to less than 5 miles an hour, for otherwise he will reach the contactor C⁸ prematurely and will therefore have the service brakes automatically applied. The special signal D, beyond which the train must not pass at danger, controls the contactor C⁹ which also is connected to negative battery. Contactor C¹⁰ however is not connected up at all under these circumstances, so that even if the driver has properly controlled his train past all the contactors supplied with negative potential, namely, C⁵, C⁶, C⁷, C⁸, and C⁹, if he does pass the final contactor C¹⁰, he will have his brakes automatically applied.

It will be noted that upon a train passing a cautionary signal an audible alarm is given and a time mechanism set in operation. The next contactor is placed preferably at such a distance from the next stop signal so that if the engineman disregards the cautionary signal and audible warning, an automatic brake application will be received at a second contactor.

When a train passes a signal at danger, as is the signal C, an audible alarm is sounded and the time signal set in operation at C⁶, again at C⁷ and also at C⁸.

When a train passes a special signal at danger, as is the signal D, the last encountered contactor C¹⁰ is not energized and therefore if this contactor is passed an automatic brake application will be made.

An example of the nature of control effected by the signal arrangement shown in Fig. 3 will now be described. As the signal A is at clear a train going, for instance at 60 miles an hour, can pass without having its brakes automatically applied. In this case the signal lever L¹ is in the down position and positive battery is connected by the switch S¹ to the contactors C¹ and C². The signal B is in the cautionary position, that is to say the signal lever L² is in an intermediate position, and positive battery is connected to the contactors C³ and C⁴, while negative battery is connected to contactor C⁵. Under these circumstances the engine driver receives a warning signal advising him that the next signal is at danger, and that he should therefore reduce his speed. The position of the contactor C⁶ in relation to the contactor C⁵ is such that a train passing between these two contactors will reach the second contactor within a predetermined time if the speed has not been reduced below a certain limit, for instance 25 miles an hour. The timing device 130

on the locomotive is set accordingly, and of course can be varied on different locomotives, so that the speed regulation curve can be modified to suit the nature of traffic, that is to say, a locomotive of a heavy goods train would have a different adjustment from the locomotive of a high speed passenger train. Consequently the distance between contactors C^5 and C^6 is fixed. This distance would be equal to the distance between the contactors C^2 and C^3 . The signal C is at danger, and the lever L^3 being in a vertical position causes the switch S^3 to connect negative battery to the contactors C^6 , C^7 and C^8 . The distance between C^6 and C^7 need not be any fixed amount, although it could be if thought desirable. Usually, however, C^6 and C^7 would be quite a considerable distance apart. The contactors C^7 and C^8 however are arranged at a distance apart which is considerably less than the distance between the contactors C^5 and C^6 , as the purpose of these two contactors is to prevent the train proceeding any further without having the brakes automatically applied if the speed has not been reduced below a very low limit, say five miles an hour. The distance between the contactors C^7 and C^8 is the same as between contactors C^4 and C^5 , and between contactors C^1 and C^2 . The train can therefore still proceed at the low speed of five miles per hour or less past the contactor C^9 , but it must not go beyond C^{10} , otherwise it will have the brakes automatically applied and so be brought to rest. The polarity of contactor C^9 is controlled by the switch S^4 which is associated with the special signal D. The curve below the figure illustrates how the speed of the train should be reduced by the engine-man to avoid having his brakes automatically applied and yet showing how he is permitted to approach as far as possible towards the signal. By placing the contactors so as to enforce a speed reduction such as indicated by the curve plotted in the lower part of Fig. 3, it will be appreciated that the danger of an accident due to carelessness on the part of an engine-driver is eliminated.

In Fig. 1 it will be noted that there is a device shown for engaging with a projection 31 on the lower end of armature 19. This device is a cancelling device which is for restoring all parts to normal after an automatic application has occurred. This device consists of an arrangement for rotating the armature 19 in an anticlockwise direction, and so closing the valve 20. The pawl 30 is normally held out of engagement with projection 31 on armature 19 by means of the air pressure behind diaphragm 32 from chamber 8. When however chamber 8 is exhausted due to an automatic brake application the spring 33 anchored to arm 34 forces pawl 30 into the path of movement of 31, owing to the absence of pressure behind the diaphragm 32. If the

cancelling device is now moved over in a clockwise direction, armature 19 will be moved to the right and will close valve 20. Air from the main reservoir can then recharge chamber 8 through the restricted orifice 35 and valves 44 and 13 will be again restored to normal. As the pressure builds up in chamber 8 and line 9, the piston 8^a is actuated to again close valve 44 and as the diaphragm 32 is again put under pressure, it presses the pawl 30 out of engagement with 31 permitting the armature 19 to restore to its neutral position.

It will thus be appreciated that by means of the invention a train control system has been evolved in which the engine-man, if alert, may forestall the application of the brakes by the automatic train stop device. A distinct warning is given when a cautionary signal is passed. A time interval is then allowed to permit the engine-man, if alert, to apply the brakes in the usual manner so that his train can be brought to a stand-still within the braking distance provided, that is to say within the over-lap normally provided beyond an automatic stop signal. If he fails to perform his ordinary duty in this manner, then an automatic brake application is given.

Similar opportunities are given when approaching stop signals, a lower range of speed being provided by the closer setting of the ramps. An engine-man may, therefore, if alert, pass an automatic stop signal without any interference by the train control device whatever. In other words an engine-man, if alert, would not know that train control was in force, except for the audible warning he receives when passing a caution signal.

In foggy weather, snow storms, etc., the additional positive assurance which he obtains when passing all signals is an improvement over known systems.

I claim:—

1. In a train control system, a locomotive, brake controlling arrangements on said locomotive, an electromagnet for operating said brake controlling arrangements, a large capacity condenser connected in circuit with said electromagnet, and means co-operating with apparatus at the side of the track to enable said condenser to be charged and so effect the operation of said electromagnet.

2. In a train control system, a locomotive, brake controlling arrangements on said locomotive, an electromagnet for operating said brake controlling arrangements, an electrolytic cell connected in circuit with said electromagnet and means co-operating with apparatus at the side of the track to enable said electrolytic cell to be charged and so effect the operation of said electromagnet.

3. In a train control system a locomotive, brake controlling arrangements on said locomotive, an electromagnet for operating said brake controlling arrangements, a plu-

rality of electrolytic cells in series with one another connected in circuit with said electromagnet, and means co-operating with apparatus at the side of the track to enable said electrolytic cells to be charged and so effect the operation of said electromagnet.

4. In a train control system, a locomotive, brake controlling arrangements on said locomotive, an electromagnet for operating said brake controlling arrangements, a plurality of electrolytic cells connected in series with each other, and permanently across the terminals of said electromagnet and means co-operating with apparatus at the side of the track to enable said electrolytic cells to be charged and so effect the operation of said electromagnet.

5. In a train control system, a locomotive, brake controlling arrangements on said locomotive, an electromagnet for operating said brake controlling arrangements, a large capacity condenser permanently connected across the terminals of said electromagnet and a current collecting shoe adapted to engage with apparatus at the side of the track to complete a charging circuit for said condenser to enable the condenser to effect the operation of said electromagnet.

6. In a train control system, a locomotive, brake controlling arrangements on said locomotive, a valve adapted to be opened mechanically by apparatus at the side of the track to cause the brake controlling apparatus to operate, an electromagnet adapted to be energized by apparatus at the side of the track, a second valve adapted to be operated by said electromagnet when energized to render the operation of said first valve ineffective, and means for preventing said electromagnet from operating said second valve under certain conditions even though it is energized.

7. In a train control system, a locomotive, brake controlling arrangements on said locomotive, an air pipe connected to said brake controlling arrangements, a valve in said pipe adapted to be opened mechanically by apparatus at the side of the track to cause the brake controlling arrangements to operate, and means adapted to be automatically operated shortly after said valve is opened to cause the closure of said air pipe at another point.

8. In a train control system, a locomotive, brake controlling arrangements on said locomotive, an air pipe connected to said brake controlling arrangements, a valve in said air pipe adapted to be opened mechanically by apparatus at the side of the track to cause the brake controlling apparatus to be operated to apply the brakes, and a magnetically actuated valve in said air pipe also adapted to be operated by apparatus at the side of the track subsequent to the opening of the

first valve to close said air pipe and render the opening of said first valve ineffective.

9. In a train control system, a locomotive, brake controlling arrangements on said locomotive, means for positively operating and mechanically locking said brake controlling arrangements adapted to be controlled from apparatus at the side of the track, and means for automatically preventing said operated and locked brake controlling arrangements becoming effective to cause a brake application, also controlled from apparatus at the side of the track.

10. In a train control system, a locomotive, an air pipe for controlling the operation of the brakes, a valve in said air pipe adapted to be opened by apparatus at the side of the track, and a magnetically actuated valve in said air pipe adapted to be closed by apparatus at the side of the track to effect the closure of said first valve.

11. A train control system comprising a locomotive, an air pipe on said locomotive, for controlling the application of the brakes, a valve adapted to be opened by apparatus at the side of the track, a second valve in said air pipe adapted to be closed by apparatus at the side of the track and means for preventing said second valve being similarly operated for a predetermined time.

12. A train control system comprising a locomotive, brake controlling arrangements on said locomotive, a timing device on said locomotive, a track, a ramp at the side of said track, a second ramp at the side of said track, a shoe on the locomotive adapted to engage successively said first and said second ramps, means controlled by said shoe for enabling said brake controlling arrangements to operate, a second means controlled by said shoe for initiating the operation of said timing device and preventing said brake controlling arrangements from operating and means controlled by said timing device to prevent said second means from exerting a similar controlling effect for a predetermined time.

13. A train control system comprising a locomotive, brake controlling arrangements on said locomotive, a timing device on said locomotive, a track apparatus at the side of the track, a second apparatus at the side of the track, apparatus on the locomotive adapted to be influenced successively by said first and said second apparatus, means mechanically operated by said locomotive apparatus for positively causing said brake controlling arrangements to operate after a predetermined interval, means controlled by said locomotive apparatus before said interval has expired for initiating the operation of said timing device and preventing said brake controlling arrangements from operating, and means controlled by said timing device to pre-

vent said means from exerting a similar controlling effect for a predetermined time.

14. A train control system comprising a locomotive, brake controlling arrangements on said locomotive, a timing device on said locomotive, a track apparatus at the side of the track, a second apparatus at the side of the track, apparatus on the locomotive adapted to be influenced successively by said first and 10 said second apparatus, means mechanically operated by said locomotive apparatus for insuring the operation of said brake controlling arrangements, an electromagnet controlled by said locomotive apparatus for initiating the operation of said timing device and preventing said brake controlling arrangements from operating, and means controlled by said timing device to prevent said electromagnet from exerting a similar controlling effect for a predetermined time.

15. A train control system, comprising a locomotive, an air pipe on said locomotive for controlling the application of the brakes, a timing device on said locomotive, a track, a 25 ramp at the side of the track, a second ramp at the side of the track, a shoe on the locomotive adapted to be influenced successively by said first and second ramps a valve mechanically operated by said shoe to open said air pipe, a second valve in said air pipe, an electromagnet controlled by said shoe for initiating the operation of said timing device and for closing said valve to prevent the opening of said valve from becoming effective and a locking member controlled by said timing device to prevent said electromagnet operating said second valve in a similar manner for a predetermined time.

35 16. A train control system comprising a locomotive, brake controlling arrangements on said locomotive, a timing device on said locomotive, means for actuating said timing device at the same constant speed irrespective of the speed of the locomotive, a track, apparatus at the side of the track, apparatus on the locomotive adapted to be influenced in different ways by said apparatus, means for preventing the application of the brakes controlled by said apparatus when operated from 50 the track in either of two ways, and means for initiating the operation of the timing device adapted to be operated when said apparatus is operated in a particular way only.

55 17. A train control system comprising a locomotive, an air pipe for controlling the application of the brakes on said locomotive, a timing device on said locomotive, a track apparatus at the side of the track, apparatus on 60 the locomotive adapted to be influenced in different ways by said apparatus, a valve in said air pipe adapted to be closed when said locomotive apparatus operates in either of two ways, and means for initiating the operation of the timing device adapted to be oper-

ated when said apparatus is operated in a particular way.

18. A train control system comprising a locomotive, an air pipe controlling the application of the brakes on said locomotive, a timing device on said locomotive, a track, a ramp at the side of the track, a shoe on the locomotive adapted to receive current from said ramp, a valve in said air pipe, electromagnetic means connected in circuit with said shoe and adapted to respond to different kinds of current and to close said valve whatever kind of current operates it, and to initiate the operation of the timing device only when a particular kind of current operates it.

19. A train control system comprising a locomotive, an air pipe on said locomotive for controlling applications of the brakes, a timing device on said locomotive, a track, a ramp at the side of the track, a shoe on the locomotive adapted to engage said ramp, a valve in said air pipe adapted to be mechanically opened by said shoe when engaging said ramp, electromagnetic means adapted to respond to current received by said shoe from 25 said ramp in different ways, a second valve controlled by said electromagnetic means whichever way it is operated to close said second valve, and means for initiating the operation of the timing device when said electromagnetic means are operated in a particular way only.

20. A train control system comprising a locomotive, an air pipe for controlling the application of the brakes on said locomotive, a timing device on said locomotive, a track, a ramp at the side of the track, a shoe on the locomotive adapted to be influenced in three different ways by said ramp, a valve in said air pipe adapted to be closed mechanically 305 by said shoe when passing a ramp, a second valve also in said air pipe, a polarized electromagnet connected in circuit with said shoe and adapted to close said second valve whether energized by current flowing in one direction or the other and means for initiating the operation of a timing device adapted to be operated when said polarized electromagnet responds to current flowing in one direction only.

21. In a train control system, a locomotive, an air pipe adapted to control the application of the brakes, a valve in said pipe adapted to be opened mechanically by apparatus at the side of the track to cause the brake controlling arrangements to operate, a large capacity condenser, an electromagnet shunted by said large capacity condenser and adapted to be operated shortly after said valve is opened to cause the closure of said air pipe.

22. In a train control system, a locomotive, brake controlling arrangements on said locomotive, means for positively operating said brake controlling arrangements adapted to be controlled from apparatus at the side 130

of the track, a large capacity condenser, means for charging said large capacity condenser from apparatus at the side of the track, and an electromagnet adapted to be energized from said charged condenser to positively prevent said brake controlling arrangements from becoming effective.

23. In a train control system, a locomotive, brake controlling arrangements on said locomotive, a polarized electromagnet adapted to exert different controlling effects on said brake controlling arrangements, a large capacity condenser connected in circuit with said polarized electromagnet and means co-operating with apparatus at the side of the track to enable said condenser to be charged and so effect the operation of said polarized electromagnet according to the nature of the charge.

24. In a train control system, a locomotive, an air pipe adapted to control the application of the brakes, a valve in said pipe adapted to be opened mechanically by apparatus at the side of the track to cause the brakes to be applied, a polarized electromagnet adapted to be operated in different ways to effect the closure of said air pipe, and means for energizing said polarized electromagnet from apparatus at the side of the track shortly after said valve is opened.

25. In a train control system, a locomotive, brake controlling arrangements on said locomotive, means for positively operating said brake controlling arrangements adapted to be controlled from apparatus at the side of the track, and a polarized electromagnet also controlled from apparatus at the side of the track and adapted to positively prevent said brake controlling arrangements becoming effective whichever way it is operated.

26. In a train control system, apparatus on the locomotive operative to control the application of the brakes, a valve adapted to be operated to neutralize the effect of the action of said apparatus, a polarized electromagnet, an armature for said electromagnet and means actuated by said armature to cause said valve to close irrespective of the direction of movement of said armature.

27. In a train control system, apparatus on a locomotive, comprising an air pipe controlling the application of the brakes, a valve in said air pipe adapted to control the passage of air through said air pipe, a polarized electromagnet, a centrally pivoted armature for said polarized electromagnet, and a sliding member rigidly connected to said valve and having projecting members engaging said armature on each side of said pivot so as to cause the valve to move in one way irrespective of the direction in which the armature is caused to move due to current flowing through said polarized electromagnet.

28. In a train control system, a locomotive,

brake controlling arrangements on said locomotive, a shoe adapted to engage with apparatus at the side of the track, a polarized electromagnet in circuit with said shoe, means for preventing the application of the brakes when a polarized electromagnet is energized by current flow through it in either direction and a timing device adapted to be set in operation when the current flow is in a particular direction.

29. In a train control system, a locomotive, an air pipe on said locomotive for controlling the application of the brakes, a valve for said air pipe, a shoe for engaging with apparatus at the side of the track, a polarized electromagnet connected in circuit with said shoe and adapted to operate said valve irrespective of the direction of current flow, a timing device adapted to be operated when the polarized electromagnet is energized by current flow in one direction and means controlled by said timing device to prevent said polarized magnet operating under the latter condition for a predetermined time.

30. A train control system comprising a locomotive, brake controlling arrangements on said locomotive, an electrically controlled timing device on said locomotive, a track, apparatus at the side of said track, apparatus on said locomotive adapted to co-operate with said track apparatus to initiate the operation of said timing device only if the track apparatus is in a particular controlling condition, a second apparatus at the side of said track, means for causing brake controlling arrangements to operate if the second track apparatus exerts a similar control to said first track apparatus on said locomotive apparatus before the timing device has been in operation for a predetermined time and an audible signal adapted to be given while the timing device is in operation to warn the driver to reduce his speed before the predetermined time has elapsed.

31. In a train control system, apparatus on a locomotive comprising an air pipe, a valve controlling said air pipe, a timing device, a turbine wheel for operating said timing device, and a jet through which air is adapted to pass when said valve is opened to operate said turbine.

32. In a train control system apparatus on a locomotive comprising an air pipe, a valve controlling said air pipe, a timing device, electromagnetic means for opening said valve, a nozzle to which air is connected when said valve is opened, a turbine adapted to be driven by air passing through said nozzle to control the operation of said timing device, and means controlled by said timing device for closing said valve after a predetermined time.

33. In a train control system apparatus on a locomotive comprising an air pipe, a valve controlling said air pipe, a timing device,

electromagnetic means for opening said valve, a nozzle to which air is connected when said valve is opened, a turbine adapted to be driven by air passing through said nozzle to control the operation of said timing device, an audible signalling device adapted to be operated as long as said valve is open and means controlled by said timing device for closing said valve after a predetermined time.

34. In a train control system, apparatus on a locomotive comprising an electromagnet adapted to be energized from apparatus at the side of the track, a valve controlled by said electromagnet for preventing the application of the brakes, a timing device, an audible signal, a second valve controlled by said electromagnet for causing the operation of said timing device and said audible signal, a locking member adapted to be operated by said second valve to prevent said electromagnet again operating in a similar manner to control said first valve, and means controlled by said timing device for removing said locking member a predetermined time.

35. In a train control system, a locomotive, brake controlling arrangements on said locomotive, apparatus mechanically operated by apparatus at the side of the track for effecting the application of the brake controlling arrangements, an electromagnet adapted to be energized in two ways by apparatus at the side of the track for preventing said brake controlling arrangements becoming effective, a timing device adapted to be operated by said electromagnet when energized in one way, means controlled by said electromagnet to prevent said brake controlling arrangements from becoming effective when said electromagnet is energized in either direction and means controlled by said timing device for preventing the electromagnet for a predetermined time when operated in one way only from operating said brake preventing means.

36. In a train control system, a locomotive, an air pipe on said locomotive for controlling the application of the brakes, a valve for said air pipe, a shoe adapted to be controlled from apparatus at the side of the track to mechanically operate said valve to open said air pipe, a polarized electromagnet, a second valve in said air pipe adapted to be closed when said electromagnet is energized in either of two directions, a timing device adapted to be set in operation when said electromagnet is energized in one direction and means controlled by said timing device for preventing said electromagnet being effective when energized in one direction, while permitting it to be effective when energized in the other direction.

37. A train control system comprising a track, a ramp at the side of the track, switching means adapted to place said ramp in three distinct conditions, a locomotive, means

on said locomotive responsive to one condition to cause the brakes to be applied, a timing device on said locomotive, means responsive to said second condition to cause said timing device to operate, means under the control of said timing device adapted to cause the brake controlling arrangements to operate if another ramp in a similar condition is passed before the timing device has completed its operation, and means responsive to the third condition for automatically preventing the operation of the brake controlling arrangements from becoming effective.

38. In a train control system, apparatus on a train comprising a shoe adapted to be moved bodily when passing over a ramp, an air pipe for controlling the application of the brakes, a valve adapted to be forced open by the mechanical movement of said shoe and locked open to allow the brakes to be applied, a second valve in said pipe, an electromagnet controlled by apparatus at the side of the track for closing said second valve in said air pipe, and means for automatically removing the locking condition of said first valve when said second valve is closed.

39. In a train control system, a locomotive, brake controlling arrangements on said locomotive, a low resistance electromagnet connected in series with said shoe, a large capacity condenser connected across the terminals of said electromagnet and adapted to assist its operation, a second electromagnet of high resistance connected in parallel with said first electromagnet and adapted to respond only to a prolonged energization, contacts controlled by said second electromagnet and a resistance shunted by said contacts and adapted to be inserted in series with said first electromagnet when said second electromagnet is energized.

40. A railway signalling system comprising a track, a plurality of signal controlling arrangements, three ramps associated with each signal controlling arrangement and switching means controlled by said signal controlling arrangements for connecting three different combinations of electrical connections to said ramps.

41. A train control system comprising a track, a ramp located alongside said track, a second ramp located alongside said track and situated a predetermined distance from said first ramp, a third ramp located alongside said track and situated a predetermined distance from said second ramp, said second predetermined distance being considerably greater than said first predetermined distance, a source of electrical energy, means for connecting one terminal of said source of electrical energy to said second and third ramps and for connecting the other terminal of said source to said first ramp if a passing train is to reduce its speed from a maximum to an intermediate speed, and means for con-

necting the last mentioned terminal of said source of electrical energy to said first, second and third ramps if said train is to pass at a minimum speed.

42. A train control system comprising a track, a signalling arrangement located alongside said track, two ramps located alongside said track at a predetermined distance from each other and associated with said signalling arrangement, switching means controlled by said signalling arrangement and adapted to selectively connect either of two kinds of electrical energy to both of said ramps or the second of said ramps or neither of said ramps, a second signalling arrangement, a third ramp associated with said signalling arrangement and adapted to be located at a predetermined distance from said second ramp, said second predetermined distance being greater than said first predetermined distance, and switching means controlled by said second signalling arrangement for connecting a similar kind of electrical energy to said second ramp or not.

43. A train control system comprising a plurality of signalling arrangements, three ramps associated with each signalling arrangement one of said ramps being located a predetermined distance from the nearest ramp associated with the preceding signalling arrangement, the other two ramps being located a predetermined distance from each other less than said first predetermined distance, a battery having its positive pole connected to one rail of the track, a second battery having its negative pole connected to one rail of the track, switching means associated with each signalling arrangement adapted to connect the positive pole of said second battery to the three ramps associated therewith when the track is clear, to connect positive pole of said second battery to the first two ramps and the negative pole of said first battery to the third ramp when the succeeding signalling arrangement is at danger and to connect negative pole of said first battery to all three ramps when the associated signalling arrangement is at danger.

44. In a combined manual and automatic brake controlling mechanism, a hand lever having an arm, a piston acting on said arm to cause an automatic brake application, said hand lever adapted to move in a curve and adapted to move up and down relatively to the surface of said piston, while said arm is operated lineally with respect to said piston.

45. In a locomotive brake controlling mechanism, a branched lever having one branch free for use in manual operation, a cylinder having a pneumatically operated piston, a second branch of said lever extending into said cylinder into engagement with said piston and adapted to be operated thereby, and a third branch of said lever pivoted outside but adjacent to the wall of said cylinder, about which the other branches rotate.

46. In a locomotive brake controlling mechanism, a branched lever having one branch free for use in manual operation, a cylinder having a pneumatically operated piston, a second branch of said lever extending into said cylinder into engagement with said piston and adapted to be operated thereby, and a third branch of said lever pivoted outside but adjacent to the wall of said cylinder which the other branches rotate, the said second branch being so located with respect to the third branch that it is free to be moved lineally within said cylinder for a distance sufficient to rotate the lever through substantially one fourth the arc of a circle.

In testimony whereof I affix my signature.

ALFRED ERNEST HUDD.
